SECONDARY OR STORAGE BATTERY

Filed Jan. 15, 1940

FIG. 1.

INVENTOR

Lester E. Lighton
BY
Augustus B. Strongton,
ATTORNEY.

WITNESS:

Bob Mitchell.

UNITED STATES PATENT OFFICE

2,262,018

SECONDARY OR STORAGE BATTERY

Lester E. Lighton, Glenside, Pa., assignor to The
Electric Storage Battery Company, Philadel-
phia, Pa., a corporation of New Jersey

Application January 15, 1940, Serial No. 313,901

4 Claims. (Cl. 136—177)

The present invention relates to the type of storage battery shown and described in Letters Patent 2,027,310, of January 7, 1936, to Edward W. Smith, and is an improvement upon the structure shown and described in application Serial No. 254,824, filed by the same Mr. Smith, and which includes the structure of the patent plus inclined perforated baffle plates arranged in the vent tube and disposed above the cell cover.

The object of the present improvement is to insure that any liquid which may pass upward through the perforations in the baffles will drain back into the cell.

Without this drainage and under some operating conditions, the foaming of the electrolyte due to the gas escaping from beneath the gas cover through the vent will cause the foam to rise sufficiently to pass through the perforations in the baffles. While the inclined arrangement of baffles will ordinarily cause liquid, which may pass through the perforations near the high portions of the baffles, to drain back through the perforations in the lower portions of the baffles, conditions may arise in which this drainage is not sufficient and liquid may collect above the baffles where gas escaping through the perforations will cause additional foaming and may cause the foam to overflow the top of the vent.

The present invention comprises a drain duct extending from the interior of the vent tube above the low part of the baffles through the wall of the vent tube and opening downward through a shoulder in line with an opening in the upper cover of the cell.

The invention also comprises the improvements to be presently described and finally claimed.

In the following description reference will be made to the accompanying drawing forming part hereof and in which,

Figure 1 is a transverse sectional view of so much of a storage battery as is necessary for illustrating the invention; and

Figure 2 is a sectional view taken on the line 2—2 of Figure 1.

Referring to the drawing, 1 indicates a container having covers 2 and 3 spaced apart and of which the cover 2 is provided with a filling opening 4. The other or gas cover 3 is arranged below the level of the electrolyte in the cell and above the plate structure 5 of the cell. The cover 3 is provided with a vent tube 6. The vent tube 6 extends through and beyond the filling opening 4. There is an annular space between the rim of the opening and the outer surface of the tube. In a general way this is a description

of the structure upon which the present invention is an improvement.

8 is an enlarged tubular head arranged on the upper end of the tube 6 above the upper cover 5. The head 8 is provided at its base with a shoulder 9 overhanging the annular space between the tube 6 and the rim of the opening 4. 10 indicates a set of inclined perforated baffle plates arranged in the head 8. Within the wall 10 of the head is a drain duct 11 communicating at its upper end 12 with the interior of the head 8 above the low portion of the baffle plates 10. The duct 11 opens downward through the shoulder 9 in alignment with the annular space between the rim of the opening 4 and the exterior of the tube 6. The duct 11 is arranged through an enlargement 13 on the inner portion of the internal wall of the head 8.

The duct 11 provides drainage from the interior of the head 8 above the baffle plates 10 back into the cell 1.

It may be remarked that the function of the baffles is to break up and dissipate foam rising from beneath them through the tube 6 and if the liquid separated from the foam remained above the baffles additional foaming might take place above them and overflow at the top of the tube 6.

As is clearly shown in Fig. 1 of the drawing, 30 the cross-sectional area of the vent duct 11 is appreciably larger than that of the perforations in baffles 10.

I claim:

1. As an improvement upon a storage battery 35 cell having covers spaced apart and of which one has a filling opening and is arranged at the top of the cell and of which the other is arranged below the level of the electrolyte in the cell and above the plate structure of the cell and is provided with a vent tube extending through and beyond the filling opening with annular space between the rim of the opening and the outer surface of the tube, the provision of an enlarged tubular head arranged on the upper end of the 40 tube above the upper cover and having at its base a shoulder overhanging said annular space, and a set of inclined perforated baffle plates arranged in the head, said head having within its wall a drain duct communicating at its upper end with the interior of the head above the low portion of the baffle plates and opening downward through the shoulder in alignment with said annular space.

2. As an improvement upon a storage battery 45 cell having covers spaced apart and of which one

has a filling opening and is arranged at the top of the cell and of which the other is arranged below the level of the electrolyte in the cell and above the plate structure of the cell and is provided with a vent tube extending through and beyond the filling opening with annular space between the rim of the opening and the outer surface of the tube, the provision of an enlarged tubular head arranged on the upper end of the tube above the upper cover and having at its base a shoulder overlying said annular space, said head having a portion of its bounding wall provided with an inwardly disposed enlarged or thickened portion, and a set of inclined perforated baffle plates arranged in the head, said head having within the enlarged or thickened portion of its wall a drain duct communicating at its upper end with the interior of the head above the low portion of the baffle plates and opening downward through the shoulder in alignment with said annular space.

3. As an improvement upon a storage battery cell having covers spaced apart and of which one has a filling opening and is arranged at the top of the cell and of which the other is arranged below the level of the electrolyte in the cell and above the plate structure of the cell and is pro-

vided with a vent tube extending through and beyond the filling opening with annular space between the rim of the opening and the outer surface of the tube, said tube having within it above the level of the first mentioned cover a set of inclined perforated baffle plates, the provision of a drain duct communicating at its upper end with the interior of the vent tube above the low portion of the baffle plates and having its lower end located to drain into the cell through the annular space.

4. An improvement upon a storage battery cell having covers spaced apart and of which one is arranged at the top of the cell and of which the other is arranged below the level of the electrolyte in the cell and above the plate structure of the cell and is provided with a vent tube extending through and beyond the first mentioned cover, said tube having within it a set of inclined perforated baffle plates, the provision of a drain arranged at the low side of the baffles and adapted for the reception and discharge, exteriorly of said vent tube, of any liquid which may tend to collect above the baffles and give rise to additional foaming that might overflow at the top of the vent tube.

LESTER E. LIGHTON.
